UNITED STATES PATENT OFFICE.

JOHN RODGERS, OF PITTSBURG, PENNSYLVANIA.

SASH-CORD FASTENER.

SPECIFICATION forming part of Letters Patent No. 373,485, dated November 22, 1887.

Application filed October 18, 1886. Renewed October 19, 1887. Serial No. 252,822. (No model.)

To all whom it may concern:

Be it known that I, JOHN RODGERS, of Pittsburgh, in the county of Allegheny and State of Pennsylvania, have invented a new and useful Improvement in Sash-Cord Fasteners; and I do hereby declare the following to be a full, clear, and exact description thereof.

The manner of securing the weight-cords to window-sashes heretofore in most common use was to cut a groove in the edge of the sash and bore a hole at a slightly-upward inclination into the sash at the bottom of this groove, into which hole the knotted end of the cord was driven. It is a common experience that this arrangement is so liable to get out of order by the slipping of the cord out of its hole or by its jamming in the groove or breaking that it is a constant and fruitful source of annoyance and inconvenience. When any of these things happens, it is necessary to take out the sash to repair the cord, and this involves the removal of the window guides or beads and considerable time and trouble.

My invention is designed to prevent all of these disadvantages and to afford a secure but easily-released fastening for the sash-cord, by which the cord can be attached or released easily and quickly without removing the sash or the guides.

To enable others skilled in the art to make and use my invention, I will now describe it by reference to the accompanying drawings, in which—

Figure 1 is a view of the upper corner of a window-sash, partly in section, showing my improved device. Fig. 2 is a view of the box which contains the locking-cam. Fig. 3 is a view of a modification. Fig. 4 is a view of the device constructed for use with a chain. Fig. 5 is a view of a modification.

In the opposite edges of the sash *a*, at the upper end, I drill horizontally in the sash a hole of suitable size to receive a perforated box or case, *d*, (see Fig. 2,) within it, so that the end, Fig. 1, is flush with the sides of the groove *b* without and countersunk into the sash. The box or case *d* is preferably made as shown in Fig. 2, so that the hole to receive it may be drilled with an auger and the box or case *d* slipped therein with little trouble and expense.

In the vertical opening of the box or case *d* is

a cam, *e*, so journaled with relation to the front end of the box that the cord *c* can be inserted down between them with ease, but when it is drawn up the cam shall bite thereon and turn up and clamp the cord firmly against the end of box *d*. The box *d* being inserted in the hole or opening and the sash put in place, the end of the cord *c* is pushed down into the grooves *b* and through the box *d* between the cam *e* and the closed end of the box, and is then drawn back against the edge of the cam, which, having turned back to permit its downward passage, rests against it. When the cord is drawn back to fasten it, the cam turns up and clamps it firmly against the end of the box *d*. If it is desired to release the cord, it can be done by pressing down the cam by means of a piece of wire, *f*, or other thin narrow instrument inserted down in the groove *b* beside the cord *c*, as shown in Fig. 1. When the cam is thus forced back and held there, the cord *c* is released and can easily be drawn out. It may be replaced by pushing it down into the groove again, as before described.

If desired, the cam may be released by means of a key or other instrument inserted through a hole, *i*, in the side of the sash *a* and box *d*, and engaging the cam either directly or by means of a hub thereon. I prefer, however, to use the wire *f*, as it can easily be inserted down through the groove alongside the cord, and thereby obviates the necessity of cutting the sash.

The distinguishing characteristic of my improved fastener is that the locking-cam may be disengaged from the sash-cord without removing the sash from the window-frame. This is made possible by the position of the cam. The cam-box *d* is set in the hole in the sash at the base of the groove *b*, so that the axis of the cam shall be back of the cord. In this way more room is given for the motion of the cam, which may easily be pushed back by the wire *f* into the box. When the cam is set on the outside of the cord in the groove, as in prior devices, there is necessarily but little room in which the cam can work, and the bearings of the cam obstruct the groove so much that a wire rod cannot be inserted to engage and unlock the cam.

A modification of my device is a spring-actu-

ated dog, as illustrated in Fig. 3. Here *g* is the dog, and *h* the spring which holds it normally in a locked position. In inserting the cord with this device it is necessary to hold the dog back by a suitable instrument—such as the wire *f* in Fig. 1—until the cord passes it, when it may be released and will bite on the cord. I prefer, however, the cam first described, as it maintains an engaging position by its gravity, and yet swings back easily to permit the insertion of the cord without the use of a wire or instrument, *f*.

When I use the term "locking-cam" in the claim, I mean to include the spring-dog *g* and other devices acting on the same principle of permitting the insertion of the cord or chain and then clamping or locking it in the fastening by the action of the cam against the end of the box *d*, or an equivalent rigid surface or bar arranged in front of or opposite to the cam or locking device, and against which the cam clamps or fastens the cord or chain. So long as this principle is used the details of form and construction of the device may be varied without departing from my invention.

My improved fastener can be used with sash-chains with equal advantage. In such use it is desirable to make the biting-edge of the cam of proper shape to suit the form of link of the

chain used, as illustrated in Fig. 4. The cam 30 may be made with eccentrics on its opposite edges, one adapted to a cord and the other to a chain, so that it is only necessary to reverse it in the box to bring either one into use. The invention is also applicable to vertically-sliding inside shutters and doors and other analogous structures. 35

What I claim as my invention, and desire to secure by Letters Patent, is—

As a sash-cord fastener, the combination, 40 with a sash having a vertical groove of larger size than the cord extending from the top of the sash, and a hole in the sash at the base of the groove, of the box or case *d*, open at the top and bottom, set in the said hole with its 45 open top and bottom in line with the groove, and a locking-cam journaled in the box or case with its axis back of the groove, whereby the grasp of the cam on the sash-cord may be released by the wire *f* without removing the sash 50 from the window-frame, substantially as and for the purposes described.

In testimony whereof I have hereunto set my hand this 13th day of October, A. D. 1886.

JOHN RODGERS.
